ORE MILL

Benjamin J. Pugh, Helena, Mont.

Application November 25, 1947, Serial No. 787,930

3 Claims. (Cl. 241—205)

1

The present invention relates to an improved mill for reducing ores containing precious metals, and more particularly to a mill especially adapted for use in reclaiming precious metals from piles of refuse ore which have previously been worked but in which a certain percentage of the precious metal is still present.

At the present time, a great quantity of precious metal is wasted. Such metal is to be found in piles of refuse which are present at the mine. In the original mining operation it is impossible to reclaim all of the metal present in the ore. Obtaining of this residue metal has been made difficult due to an inadequate milling operation. The amount of precious metal in the refuse material does not justify the expense of hauling the material to an established mill. However, there is enough of this precious metal in the refuse material to justify its removal, provided the cost of the operation is not too excessive. So far as is known, there are no mills of a portable nature which are capable of being carried to the mine and set up for operation.

The present invention has been designed so that it is sufficiently light in weight in order that all parts may be easily carried to the site of the mine and can there be set up for operation, thereby making it possible to reclaim any precious metal to be found in this waste or refuse material at a minimum amount of expense.

The primary object of the invention, therefore, is to provide a grinding and crushing mill for reclaiming precious metals, the construction of which permits it to be readily transported and erected at the mine or on the site where the reclaiming is to be accomplished.

A further object of the invention is to provide improved means in the form of an amalgam pot for withdrawing the precious metal from the mill so that tests can easily be made to determine the percentage of metal being reclaimed from a given quantity of refuse material.

The above and other objects of the invention will in part be obvious, and will in part be hereinafter more fully pointed out.

In the drawings:

Figure 1 is a view partly in vertical section of the new and improved mill;

Figure 2 is a top plan view thereof; and

Figure 3 is a top plan view of one of the grinding and crushing elements.

Referring to the drawings for a more detailed description thereof, the new and improved mill which is generally designated by the reference numeral 5 is shown supported on a concrete base

2

6. As previously indicated, this mill is delivered in a disassembled condition to the site of the mine, and is adapted to be erected on the site where the refuse material is to be found. The first step in erecting the mill is the construction of the base 6. This base is built solidly enough to support the entire weight of the mill, and a cavity or recess 7 is formed therein for a purpose to be herein-after more fully described.

10 The mill 5 includes an open framework comprising vertically extending upright members 8 which may be of angle iron formation. These upright members are united by means of spaced transverse members 9 and 10, which members support the driving mechanism for the grinding and crushing members.

The container for the refuse material to be reclaimed is a relatively large cylindrical-shaped drum 11 which is securely fastened to the base

15 6 by means of tie rods 12. These tie rods are anchored at one end to the drum 11 as indicated at 13, while the other end thereof is securely locked within the base 6 as indicated at 14. As is

20 to be understood, a series of these tie rods are employed around the circumference of the drum for holding said drum in locked position on the base. Any desired means, not shown, may be employed for delivering the refuse material through the open end of the drum 11, and as is

25 conventionally practiced, a stream of water is fed into the drum to be mixed with the refuse material. One means of feeding water into the drum is shown in Figure 1 of the drawing, which includes a feed pipe 15 having a control valve 16

30 mounted in the line, said pipe terminating in the bottom wall of the drum, as indicated at 17. Thus, a steady and regulated stream of water is fed into the drum 11 for mixture with the refuse material which is fed in from the upper end of

35 said drum.

The mill 5 further includes a pair of grinding disks 18 and 19, respectively. The grinding disk 18 is fixedly mounted against rotation on the bottom wall 20 of the drum 11 by any desired

40 means. The grinding disk 19 is mounted for rotation relative to the grinding disk 18, and the meeting faces of said disks are tapered and beveled as indicated at 21 to give a crushing effect to the refuse ore during the action of the mill.

45 In other words, as seen in Figure 3 of the drawings, tapered lands 22 are formed on the meeting faces of the disks so that as the rotating grinding disk 19 is driven, it will ride up on the tapered and beveled face of the stationary grinding disk

50 18. As this action takes place, the refuse ore

will move between the meeting faces of the disks and upon continued rotation of disk 19, will be ground and crushed between the faces of said disks.

The means for rotating the disk 19 includes a fixed vertically extending hollow shaft 23 and a second tubular shaft 24. The second shaft 24 completely encases the major portion of the hollow shaft 23. The lower end of the hollow shaft 23 is formed with a multiplicity of spaced perforations 25, for a purpose to be hereinafter more fully described. The upper end of the shaft 23 is fixedly held within the member 10. A relatively large gear wheel 26 is mounted for rotation on the shaft 23, said gear wheel being slightly spaced above the member 9. Journalled between the members 9 and 10 and in mesh with the gear wheel 26, are a pair of long pinions 27 and 28. The shaft of the pinion 28 is driven from a gear 29 which is in mesh with a worm 30 driven by a shaft 31. The shaft 31 may be driven by any desired means, there being illustrated a pulley wheel 32 on which may be mounted a driving belt extending from a motor located at a remote point, and not shown in the drawing. The mechanism just described forms one means for imparting rotation to the grinding disk 19, and at the same time permits said disk to move vertically on the tubular shaft 24.

The grinding disk 19 is mounted for rotation with the shaft 24. The means of connecting the grinding disk 19 to the shaft 24 comprises a bracket 33 having a sleeve 34 secured to the shaft 24. The bracket 33 further includes laterally extending arms 35 which are attached to the grinding disk 19 by means of bolts 36. From this construction it will be seen that as the shaft 24 is rotated, it will carry with it the bracket 33 and grinding disk 19. Of course, the upper end of the shaft 24 carries a collar 37 which is attached by any desired means to the gear wheel 26 for rotation therewith.

By means of the construction previously described, the refuse ore or precious metal-bearing mass is ground and crushed to a relatively fine state so that all precious metal contained therein will be released. In accordance with the present invention, a small quantity of mercury is deposited within the drum 11, and as the metal within the crushed ore is released, it will be attracted to the mercury and pass therewith through the perforations 25 in the lower end of the shaft 23. Thus, this perforated end of the shaft 23 becomes in effect an amalgam pot, and the collection of metal and mercury will pass from the perforated end of the shaft downwardly into a collection tube 38. This collection tube 38 is suitably secured to the bottom wall of the drum 11 and is embedded within the base 6. The lower end of the collection tube, however, is disposed within the recessed portion 7 in the base. That area of the collection tube which is disposed within the recess carries a shut-off valve 39 of conventional construction, and a cap 40. The cap 40 is screwed on the end of the pipe and is formed with a lever 41 to facilitate removal and placement thereof. If desired, additional bolts 42 may be employed for locking the base of the drum 11 onto the concrete base 6. The heads of these bolts are accessible from the recess 7. These bolts may also serve to retain the collection pipe retaining flange and washer which are designated by the reference numeral 43 in position.

It is thought that the operation of the ore

mill is readily obvious from the above description when taken in connection with the accompanying drawing. A motor or other means is employed for driving the worm gear 30 and its shaft

5 31, rotation of which drives the gear 29 and pinion 28. As the pinion 28 is rotated, it will in turn drive the meshed gear wheel 26 and the other pinion 27. As the gear wheel 26 rotates, the shaft 24 will likewise be rotated, carrying with 10 it the grinding disk 19. As the grinding disk 19 is rotated, it will rise and fall on the beveled and tapered face of the stationary grinding disk 18, and this continual rising and falling and rotary movement of the grinding disk 15 will crush and grind the refuse ore material which is being lodged between the faces of the grinding disks to a very fine state. The refuse material is being constantly fed into the drum 11 and mixes with the water which is 20 admitted into the drum through the feed pipe 15. As the refuse material is crushed into a very fine state, the precious metal will be released and immediately attracted to the mercury which is present within the drum. The mercury and the 25 attracted metal will then flow through the perforations 25 downwardly into the collection tube 38, the valve 39 being open to allow for the collection of the freed metal.

From time to time the operator of the mill may 30 want to make a test to determine the amount of precious metal which is being recovered from a certain quantity of refuse material which has been fed into the drum. This can readily be determined by first closing the valve 39 and then 35 removing the cap 40, thereby allowing the recovered metal to be deposited in a pan 44. By weighing the amount of recovered material in the pan 44, he can readily determine the approximate value of metals to be obtained per ton from the 40 pile of refuse ore. Also, from time to time the valve 39 will be closed and the cap removed for collection of the metal which has been recovered within the amalgam pot.

As the amalgam pot proper is between the valve 45 39 and cap 40, it takes about thirty pounds of mercury to fill the amalgam pot and to extend part way back on the disk so that the drop of the disk splashes the mercury to all the lower parts of the mill, bringing it in contact with the freed 50 parts of precious metal.

It is obvious that many changes may be made in the details of construction without departing from the spirit of the invention as set forth in the appended claims.

55 Having thus described my invention, what I claim as new and useful is:

1. In an ore grinding mill of the character described for recovering precious metals, a base, a frame detachably mounted on said base, an ore receiving drum supported in said frame and on said base, a grinding disk fixedly mounted on the bottom of said drum, a hollow shaft rising centrally of said disk and upwardly through said frame, the lower end of said shaft mounted with 60 in said disk being perforated, a second shaft for vertical sliding movement surrounding said first mentioned vertical shaft and rotatable relative thereto, a second grinding disk rigidly attached to said last named rotatable shaft in close 65 proximity to said stationary disk, a series of inclined portions formed on the meeting faces of said grinding disks extending about angular distances of approximately 90 degrees, and means whereby said second grinding disk will be rotated and reciprocated relative to said stationary 70 75

disks the inclined portions on said grinding disks providing mutually engaging spiral grinding surfaces.

2. In an ore grinding mill of the character described for recovering precious metals, a base, a frame detachably mounted on said base, an ore receiving drum supported in said frame and on said base, a grinding disk fixedly mounted on the bottom of said drum, a hollow shaft rising centrally of said disk and upwardly through said frame, the lower end of said shaft being perforated, a second shaft surrounding said vertical shaft and mounted for rotatable and vertical sliding movement relative thereto, a second grinding disk attached to said second rotatable shaft in close proximity to said stationary disk in series of spiral inclined portions formed on the meeting faces of said grinding disks, a collection tube mounted in said base and in communication with said perforated tube for receiving the recovered metal released from the ore by said disks, and means whereby said second grinding disk is rotated and reciprocated relative to said stationary disk for grinding and crushing the ore

within the drum to separate the precious metal therefrom said spiral portions forming mutually engaging grinding surfaces extending an angular distance of at least 90 degrees.

5 3. The structure as set forth in claim 2, wherein means are provided within the base for recovering the metal received within the collection tube.
